(57) **CLAIM**

The ornamental design for a carrier for wine bottles, as shown and described.

DESCRIPTION

FIG. 1 is a perspective view of a carrier for wine bottles showing our new design.

FIG. 2 is an end elevational view thereof.

FIG. 3 is a front elevational view thereof.

FIG. 4 is a rear elevational view thereof.

FIG. 5 is a top plan view thereof; and,

FIG. 6 is a bottom plan view thereof.

The broken line showing of a bottle in FIG. 1 and the broken lines shown on the surface of the claim is included for the purpose of illustrating environmental structure only and forms no part of the claimed design.
